UNITED STATES PATENT OFFICE

2,460,551

UNITARY TUMBLER CYLINDER LOCK

Gunnar E. Swanson, New Britain, Conn.

Application June 16, 1945, Serial No. 599,877

5 Claims. (Cl. 70—364)

1

This invention relates to cylinder locks of the locking bar and unit spring type. Such a lock is shown in my prior Patent No. 2,206,539 for Cylinder lock, dated July 2, 1940. Unit tumblers, that is, tumblers which are integral with their springs and the springs connected with each other, are formed of thin resilient metal.

The object of the invention is to so construct the cylinder and tumbler unit that the unit can be sprung into place in the cylinder and be retained and supported in such manner that the springs will have full and free action without liability of being distorted and the tumblers have sure and easy co-operation with the locking bar without danger of becoming jammed by use.

In the accompanying drawings

Fig. 1 is a longitudinal section on plane denoted by the dotted line 1—1 on Fig. 2 of a cylinder lock that embodies the invention.

Figure 2 is a transverse section on plane indicated by dotted line 2—2 of Fig. 1, showing the elements as in locked relation.

Figure 3 is a similar section showing the parts as when unlocked by the insertion of a correct key.

Figure 4 is a detail view of part of the tumbler unit.

Figure 5 on enlarged scale shows a blank from which a tumbler unit is formed.

In the views 1 indicates the barrel, 2 the cylinder and 3 the locking bar which is carried by the cylinder and is normally moved outward by the tumblers so as to extend into a slot or groove in the barrel and hold the cylinder from turning and is pressed inward by springs 4 that engage its ends, so as to release the cylinder and allow it to be turned when the correct key 5 is inserted and the tumbler notches 6 are so aligned that they will receive the locking bar.

The blank of thin flexible metal from which the tumbler unit shown is formed has a base plate 7 from which extend separated spring fingers 8 that at their free ends have transversely extending tumbler blades 9 and reinforcing lugs 10. In shaping this blank the reinforcing lugs are folded over to increase the thickness of the fingers, the outer edges 11 of the tumbler blades are bent at right angles transversely of their length so as to increase the width of their ends, the spring fingers are curved backward, then forward from the base plate so that they will have maximum flexibility and are twisted ninety degrees, as at 12, in order that the tumblers extend downward in the plane of action of the spring fingers.

2

The cylinder is preferably die cast with a cavity or recess 13 for the spring fingers, and with a longitudinal slot 14 for the key. The cylinder has integrally formed spacing plates which project into the recess 13 and which are separated by slots 15 that extend transversely on each side of the key slot for receiving and guiding the ends of the spring fingers and the tumblers. The cylinder also has a longitudinal slot 16 in its surface for the locking bar, the locking bar slot desirably extending the length of the cylinder and into the head 17 so as to permit the use of a wheel grinder for cutting the notches 6 in correct relation in the edges of the tumblers after the selected key is inserted into the cylinder.

The tumbler unit described is sprung into place in the cylinder with the ends of the base plate 7 extending into notches 18 in the end walls of the cylinder, and the reinforced ends of the spring fingers resting on the walls 19 over the key slot. In this position the upper bend of the practically S-shaped spring fingers engage the walls 20 and the tumbler blades extend down into the slots 15 in engagement with the locking bar.

From the foregoing description it will be evident that the cylinder 2 has an open-sided recess extending through a substantial portion of its length and that the locking bar slot and the key slot communicate with the said recess, being substantially perpendicular to each other. The tumbler unit is located chiefly within the recess, the base plate thereof being connected with the cylinder by means of the slot 18 and the opposite wall 20. The fingers of the tumbler are rigidly connected with the base, being preferably formed integrally therewith. The key engaging portions of the fingers are adjacent the key slot in positions to be acted upon by the key. The tumbler plates carried by the respective fingers are adjacent the locking bar and extend transversely thereof, being notched to receive the locking bar when moved by the key so that the several notches are in alignment.

As a result of the construction described the unit can be quickly sprung into place where it will retain its correct position and from which it can be readily withdrawn. Although the spring fingers are made of light stock being folded adjacent to the key slot, double thickness is provided for easing and withstanding the thrust of the bitted key when inserted and removed, and at the same time provide a stiff guide for the tumblers. And as the tumblers have their edges bent wide surfaces are provided for engagement with the locking bar and for the notches that

receive the locking bar when the correct key is inserted into the cylinders.

It will be observed that the portions 11 of the tumbler plates project transversely thereof beyond the corresponding slots 15 between the spacing plates. Thus the said portions 11 are at the outer edges of the spacing plates, that is, at the edges thereof which are adjacent the locking bar. The result is that the outer edges of the spacing plates prevent inward movements of the tumbler plates, that is, they prevent movements of the tumbler plates in the direction of inward movement of the locking bar. By reason of the engagement of the portions 11 of the tumbler plates with the outer edges of the spacing plates, the locking bar is positively held in its outer locking position except when the notches in the tumbler plates are aligned to permit inward movement of the bar. When the tumbler plates are moved by the key, they move along the said outer edges of the spacing plates.

The invention claimed is:

1. The combination in a cylinder lock, of a barrel having a central opening with a longitudinal groove therein, a cylinder rotatable in the barrel opening and provided with a longitudinally extending open-sided recess and with integrally formed spacing plates within the recess having a plurality of similar transverse slots between them which cylinder has a longitudinal key slot communicating at its inner edge with the last said slots and also has a longitudinal locking bar slot between its periphery and the said recess, a locking bar in the last said slot movable outward into the barrel groove to effect locking, and a tumbler unit comprising a longitudinal base plate connected with the cylinder within the recess and also comprising a plurality of fingers formed integrally with the base plate which fingers have resilient portions adjacent the base plate and within the recess and also have other portions extending through the respective slots between the spacing plates and positioned to be separately moved within the last said slots by a key in the key slot and the said tumbler unit further comprising tumbler plates integral with the respective fingers and projecting transversely thereof beyond the slots between the spacing plates so that the outer edges of the spacing plates prevent inward movements of the tumbler plates which tumbler plates normally engage the locking bar to hold it in its outer locking position and are notched to permit inward movement of the bar upon movement of the fingers by the proper key and upon cor-

responding movement of the tumbler plates along the outer edges of the spacing plates to align the said notches.

2. The combination in a cylinder lock as set forth in claim 1, wherein the base plate of the tumbler unit is adjacent but spaced from the end of the spacing plates in the cylinder recess, wherein the cylinder is provided with notches therein which receive the edge portions of the base plate, wherein the base plate and the fingers of the tumbler unit are collectively S-shaped, and wherein the cylinder has a longitudinal wall engaging the fingers to hold the base plate in the said notches.

3. A tumbler unit for a cylinder lock which comprises a base plate, spring fingers integral with and extending from said base plate, and tumbler blades integral with and extending from the free ends of said spring fingers, said tumbler blades having their outer edges bent angularly from the planes of the blades to provide surfaces that are wider than the thickness of the blades for the engagement of the cylinder locking means.

4. A tumbler unit for a cylinder lock which comprises a base plate, spring fingers integral with and extending from said base plate, and tumbler blades integral with and extending from the free ends of said spring fingers, sections of said spring fingers adjacent to the tumblers being folded to increase their thickness.

5. A tumbler unit for a cylinder lock which comprises a base plate, S-shaped spring fingers integral with and extending from said base plate, and tumbler blades extending from the free ends of said spring fingers, said tumblers having their outer edges bent angularly from the planes of the blades to provide surfaces that are wider than the thickness of the blades for the engagement of the locking bar, and sections of said spring fingers adjacent to the tumbler blades being folded to increase their thickness.
